UNITED STATES PATENT OFFICE.

DAVID S. BROWN, OF NEW YORK, N. Y.

DESIGN FOR SOAP.

Specification forming part of Design No. **7,930**, dated December 15, 1874; application filed December 1, 1874.
[Term of Patent 3½ years.]

To all whom it may concern:

Be it known that I, DAVID S. BROWN, of New York city, in the county of New York and State of New York, have invented a Design for Soap, of which the following is a specification:

The nature of my design is fully represented in the accompanying photographic illustration, to which reference is made.

A represents a piece of soap, one side of which is ornamented with the figure B, consisting of a crying babe resting on a pillow.

I color the piece of soap either wholly or partial, or not at all. If colored, the ground may be colored differently from the figure, or the figure may appear white and the ground

colored, or vice versa, or the whole may be given one color; but I do not consider the colors selected to be an essential element in my design.

The distinctive character of my design is found in the figure B, with which the piece of soap is ornamented.

What I claim as my invention is—

A design for soap, consisting of a crying babe resting on a pillow, substantially in the manner above described.

DAVID S. BROWN.
